TRIMMING DEVICE FOR STOCK FOR
LOOM REED DENTS

Howell F. Davis, Wickliffe, and Earl A. Southam
and Fred Crossman, Cleveland, Ohio, assignors
to The Lindsay Wire Weaving Company, Cleve-
land, Ohio, a corporation of Ohio

Application May 7, 1948, Serial No. 25,634

2 Claims. (Cl. 29—76)

1

In the manufacture of reeds for looms, it is very desirable that all of the dents be accurately of the same width so as to present a single plane to the lay strand as the batten swings against it. Any unevenness in the engaging face of the dents produces a corresponding unevenness in the fabric. This matter is of a special importance in looms for weaving wire fabric for Fourdrinier paper making machines, where even a slight projection of one dent beyond the general plane thereof in the reed, or even burrs at the edges of the dents, causes a kink or irregularity of the lay wire or damage to it which prevents the formation of the perfect wire fabric desired.

It is the object of the present invention to provide an efficient machine for trimming the edges of a ribbon of stock to bring it not only to exactly the same width throughout and render its active edges smooth, but also to remove any projecting burrs where the faces of such edges join the flat faces of the ribbon. When such treated stock is cut into proper lengths, dents are produced which when mounted in the reed present a single plane of smooth front edges to engage the lay strand.

In accomplishing our object, we take a ribbon of suitable material, preferably steel, wound up in spiral formation and feed the same between a pair of spaced abrading devices to true the opposite edges, and thereafter we feed the stock between other abrading members adapted to remove any burrs at the corners of the strip. For the edge-face trimming, we preferably provide a plurality of pairs of opposed files, such pairs being of successively finer formation. After these files have acted against the thin parallel edges of the stock, we engage the corners of the trimmed stock by trimming members preferably very fine files set at an angle to each other, there being two sets of these angularly set trimmers to act respectively against the two bottom corners of the stock and the two top corners.

An embodiment of our machine having the above general features is illustrated in the drawings hereof and is hereinafter more fully described.

In the drawings, Fig. 1 is a side elevation of our complete trimming machine; Fig. 2 is a plan of either of two surmounting and spaced guiding members between which the stock passes; Fig. 3 is a plan of a clamp carrying a pair of facing files which are clamped against opposite sides of the guiding members, the clamp being partly broken out to indicate the files beneath the top of the clamp, the convergence of the guiding members and the files slightly toward the discharge end shown in Figs. 2 and 3 being exaggerated for clearness of illustration; Fig. 4 is an elevation of

2

the clamp mounted on the guiding members; Fig. 5 is a cross section of the same in a plane indicated by the line 5—5 on Fig. 3; Fig. 6 is a plan of the device for removing the burrs from the corners of the trimmed stock; Fig. 7 is an elevation of the last-mentioned device; Figs. 8 and 9 are vertical cross sections on the correspondingly numbered lines on Fig. 7.

In Fig. 1 we have indicated an elevation of our complete trimming and smoothing mechanism associated with means for carrying a wound-up roll of untrimmed stock, means for winding up the stock after trimming, and suitable mechanism for propelling such stock. In this view 10 indicates suitable supply reel carrying in wound-up form the ribbon of stock A, which is preferably a steel ribbon having a width slightly greater than that desired for the finished dent. 12 indicates a corresponding reel for winding up the finished stock. 13 indicates a pair of feed rolls to engage opposite faces of the stock, these rolls being suitably driven, for instance by a motor 14 connected by suitable belt 15 with a driven belt pulley 16 on the shaft of one of the rolls 13.

Between the supply reel 10 and the feeding rolls 13 we have provided a table 20 which carries the trimming mechanism. On this table the first device adjacent the supply roll 10 is a suitable cleaner 21 having brushes or wipers (not shown) to engage the stock. The table carries beyond the cleaner two trimming devices 30, one acting after the other, and both identical except in their adjustment and fineness of the files they carry. Following the last trimmer is a burr remover 50 acting on the four corners of the trimmed stock.

As shown, each trimming device comprises a pair of surmounting bars 31 and 32, held with a space between them for the passage of a ribbon, and a clamping device 40 having a pair of side plates 41 each carrying an inwardly facing file 42 to provide opposed abrading members to engage opposite edges of the ribbon. Each of the members 31 and 32 is formed with a slightly converging shank 33 with lateral extensions 34 at its opposite ends. One of these members 31, rests on and is secured to the table; the other member rests on a pair of end shims 35 surmounting the heads 34 on the lower member. Suitable screws 36 pass through the upper extension 34, then through the shims and then through the lower extensions 34 and are threaded in the table top. Such screws therefore serve to hold the complete guiding device together and hold it in position on the table.

The clamp 40 comprises a pair of plates 41 each carrying on its inner face a file 42, such files being secured to the plates by suitable screws 43 coun-

tersunk in the files and threaded in the plates. 44 indicates a distance piece in the form of a bar rectangular in cross section lying between the uppermost portions of the plates 41. Between the files and this bar is a row of clamping bolts 45 which pass freely through one of the plates and are threaded in the other.

When the clamping device described is put in place with the files on opposite sides of the guiding bars 31 and 32 and the clamping screws 45 tightened, the files are clamped tightly against opposite faces of the two guides 31 and 32. Each guide member 31 and 32 and also the distance bar 44 tapers slightly toward the discharge end. This taper is preferably only a few thousandths of an inch and hence is exaggerated in Figs. 2 and 3 for clearness of illustration.

A plurality of these trimming devices, as just described, is mounted on the table for successive action on the ribbon. We have shown two of the devices. They are identical except that the second device preferably carries files of finer formation than the first and such files are slightly closer together than in the first trimmer. We have found it satisfactory to hold the discharge ends of the files of the first trimmer .003" nearer together than the entrance end thereof, and to make the entrance end of the second trimmer .001" wider than the discharge of the first one and the discharge of the second trimmer .002" narrower than its entrance.

By mounting the files removably on the removable clamping device 40, such device may be readily removed and the files replaced by fresh files whenever desired.

The result of passing the clean stock through the successive trimmers is that the two opposite edges are rendered perfectly smooth and flat and the discharged ribbon is given a definite width corresponding to the discharge width of the final trimmer. Such files, however, may leave slight burrs on the four corners of the file stock. We accordingly provide beyond the last trimmer a device for removing these burrs. Such device is illustrated in general elevation at 50 in Fig. 1 and in detail in Figs. 6 to 9 inclusive and will now be described.

As shown, the body of the first corner trimming member 50 comprises a block 51 having projecting ears 52 through which screws 53 pass into the table 20. At its top this block is provided with a substantially V-shaped recess in which are seated a pair of very fine files 55 at substantially right angles to each other and each at 45° to the edge of the stock passing between them. Surmounting the block 51 is a presser plate 56 loosely mounted on four studs 57 rising from the block 51. Each stud is surrounded by a compression spring 58, constrained by a nut 59 carried on an upper threaded portion of the stud. The adjustment of these nuts press the stock A with the desired pressure downwardly against the burr-removing files 55.

Beyond the upwardly facing corner trimmer just described for the two bottom corners of the stock, is a downwardly facing, angular trimmer for the top corners. As shown, the block 51 carries an elevated horizontal extension 60 shown as secured to the block by horizontal screws 61 passing through ears on the far end of the block. The far end of this elevated extension is supported by a block 62 to which it is secured by screws 63. The block 62 is attached to the table by screws 64 passing through bottom ears 65 on the block. In the under face of the extension 75

60 we mount a pair of very fine files 66 at right angles to each other, each at 45° to the edge of the ribbon A.

In the space beneath the extension 60 we place a plate 67, slidably mounted on four studs 68 threaded into the table top 20. The plate 67 is adjustably pressed upwardly by compression springs 69, surrounding the four studs and adjusted by nuts 70 threaded on the studs. By this means we are able to press the stock A upwardly with the desired pressure to bring its upper corners against the fine files 66 to trim off any burrs at such corners.

It will be seen that our mechanism first reduces the width of the stock to a very accurate dimension and smooths the opposed edges thereof and then trims off any burrs first at the lower corners of the stock and then at the upper corners, the stock being then discharged in perfect condition for cutting into dents. Due to the provision for regulating the pressure of the two sets of corner files against the stock we avoid any material rounding of the stock at the corners but do trim off any projecting burrs.

It is convenient to wind up the finished stock on a reel for future use and that is the way it is illustrated in Fig. 1. However, if desired it may be passed from our trimming machine directly to any suitable machine for cutting it into lengths. In either case it is only necessary to cut the finished stock into proper lengths to make perfect dents for loom reeds.

We claim:

1. In an apparatus for trimming ribbon stock, the combination of a table, a pair of rigid bars spaced in parallel relation to form a channel for ribbon stock and each having a laterally extending head at each end, means on the heads for securing the bars in spaced relation to the table, and a removable clamp having a pair of side plates adapted to enclose the open longitudinal sides between the bars and having a longitudinally extending file on the inner side of each side plate, and means on said clamp for tightening the clamp to hold the files in fixed relation against the opposite sides of the guide bars.

2. In a trimming machine, the combination of a pair of stationary ribbon guide bars extending in the same general direction and spaced apart in parallel relation, the opposite edges of the bars converging slightly toward one end, means for holding a pair of abrading surfaces in normal relation against opposite converging edges of the bars and thereby bridging the space between the bars, and means operatively associated therewith for progressing a ribbon of stock between the bars longitudinally thereof and in a direction toward their converging ends.
